Fig. 1.

Fig. 3.

Fig. 2.

Fig. 4.

FIG. 1 is a perspective view of a tire embodying my new design, it being understood that the full line portion is repeated throughout the circumference of the tire, shown by means of broken lines;

FIG. 2 is an enlarged fragmentary plan view of the full line tread portion shown in FIG. 1;

FIG. 3 is a sectional view taken substantially on the plane indicated by line 3—3 of FIG. 2;

FIG. 4 is an enlarged fragmentary elevational view of the full line tread portion shown in FIG. 1.

The dominant features of my design reside in those portions shown in full lines in the drawing.

I claim:

The ornamental design for a tire, substantially as shown and described.
